ADJUSTABLE PLATFORM LOUNGING CHAIR
Harvey H. Mohler, 5647 N. Rosemead Blvd.,
Temple City, Calif.
Filed Nov. 26, 1962, Ser. No. 239,990
1 Claim. (Cl. 297—89)

This invention relates to an adjustable article of furniture of the type having a retractable leg rest and, more particularly, relates to a platform lounger, including the best features of the platform rocker, the Morris chair and the recliner, with additional new features.

Similar to a platform rocker, a chair according to the invention has a one-piece rigid, unitary frame including the seat portion, the arms and the back, and has a base upon which it pivots, the base having the chair legs. A chair according to the present invention is balanced as is a rocker, but instead of rocking it reclines backwardly on a fixed pivot point.

Provided as a part of the invention is a leg rest panel which forms an undetectable front face portion of the chair when the chair is in the upright position. When the chair is pivoted, the leg rest automatically moves outwardly in a true arc of a circle, the seat edge being the center thereof in the preferred embodiment. This makes it possible to close the chair with a light pressure of the legs and also makes it impossible to damage the offset or remote hinge mechanism upon which the leg rest is carried and moved. It is typical in the prior art that a reclining chair is designed to be operated so not much pressure is applied on the leg rest to force the chair into its upright position, or into its reclining position. The reason for this is that in the prior art the leg rest mechanism is generally made so that damage to it would occur if the chair were returned to its upright position by applying the force only to the leg rest.

Incorporated in a chair according to the invention is an adjustable automatic control device which locks the chair in its open or fully reclined position and also locks it closed when it is in its upright or closed position. The chair is so constructed so that anyone who can rock a platform rocker can operate it and the weight of the user is unimportant.

Because the leg rest pivots on a true arc of a circle, it can be operated by hand; that is, the user may move it outwardly into its upward position by pulling on it and it thus can be used in a non-reclining chair or davenport so as to effectively form a hidden ottoman.

The hardware for this platform lounger weighs less than five pounds so as to keep it in the light weight class. It also requires less space than a conventional reclining chair in that it can be as close as seven inches to a wall and still recline fully, and with the leg rest extended it occupies less space than the conventional club chair with an ottoman.

It is an object of the present invention to provide an improved reclining chair and an improved leg rest for the latter type of chair or for a non-reclining article of furniture.

It is another object of the present invention to provide an improved reclining lounge chair which requires less space than was heretofore possible for the same size chair and the same comfort to the user.

It is still another object of the present invention to provide a reclining chair with better styling possibilities in that it has no breakaway back, and it can be used with a reversible cushion of any shape, including a T-cushion.

It is a further object of the invention to provide a new chair in the form of a platform lounger which can be operated by anyone regardless of his weight. This is made possible by having the leg rest supported on a remote

2

or offset hinge so that the leg rest moves in a true arc of a circle. The leg rest does not change its position on the legs of the user as it moves; that is, it is movable in the same true arc as the user's legs which are hinged at the knees.

5 It is a still further object of the present invention to provide a reclining chair which has a one-piece unitary frame including the seat supporting portion, the back and the side arms.

10 It is another object of the present invention to provide a reclining chair which can be conveniently supplied with a reversible cushion.

15 It is still another object of the present invention to provide an easily operated reclining chair for older people or invalids who cannot operate the conventional heavy type of reclining chair.

20 It is a further object of the present invention to provide a reclining chair for use in small apartments or in trailers or mobile homes where there is limited space.

25 It is a still further object of the present invention to provide a reclining chair with a control device which automatically locks the chair in the upright position and in the reclined position. This control device can be adjusted according to the weight of the user so that a slightly excessive pressure over that of the weight of the user applied to the back of the chair will cause it to recline and, similarly, a slightly excessive pressure over that of the weight of the user on the leg rest will cause the chair to move from its reclining position to its upright position.

30 It is another object of the present invention to provide a reclining chair with a leg rest which, in contrast to a typical recliner, requires no structural member in addition to the hinge members to hold the leg rest in its upper position.

35 It is still another object of the present invention to provide a leg rest which may be installed in a stationary chair, davenport or love seat as a disappearing ottoman which can be raised by lifting with a hand at the bottom of the leg rest panel.

40 It is a further object of the invention to provide a leg rest in a stationary chair or in a reclining or rocking chair and which can be raised by a lever on the exterior of the chair.

45 It is a still further object of the invention to provide a leg rest for any chair and which can be raised by a forward thrust on one of its offset hinge members.

50 It is another object of the invention to provide an improved leg rest operable by a link which applies a downward thrust to one of the offset hinge members.

55 It is still another object of the present invention to provide a leg rest pivotal about a virtual hinge line on offset hinge members which are damage proof in normal operation.

60 It is a further object of the present invention to provide a leg rest operable by an offset hinge, the hinge structure being connected only to the leg rest panel and to the seat or frame structure.

65 Further objects and advantages of the invention may be brought out in the following part of the specification wherein small details have been described for the competence of disclosure, without intending to limit the scope of the invention which is set forth in the appended claim.

Referring to the accompanying drawings, which are for illustrative purposes only:

FIG. 1 is a side elevational view of a chair according to the invention in its reclining position;

FIG. 2 is a front elevational view of the chair shown in FIG. 1 in its upright position;

70 FIG. 3 is a fragmentary plan view, showing the hinge mechanism and control on one side of the chair, taken substantially as indicated by line 3—3 in FIG. 2;

FIG. 4 is a fragmentary, partly cross sectional view of the chair, taken as indicated by line 4-4 of FIG. 2;

FIG. 5 is a view taken as indicated by the line 4-4 in FIG. 2 with the chair in its reclined position and the foot rest in its upwardly extended position;

FIG. 6 is a view of a portion of the control, taken as indicated by the line 6-6 in FIG. 3;

FIG. 7 is a fragmentary view of the control when the chair is in its upright position;

FIG. 8 is a fragmentary view of the control when the chair is in its reclined position;

FIG. 9 is a fragmentary view of an embodiment of the leg rest which is lever operated in a stationary chair; and

FIG. 10 is a fragmentary view of the chair having a hydraulic operating means.

Referring again to the drawings, there is shown a reclining chair having a unitary rigid frame structure 10. The frame includes a back 11, sides 12 and 13, arms 17 and 18 and a seat supporting structure 19. The back and sides are covered with upholstery, as at 20 and 23, respectively. The seat support 19 has an upholstered cushion 24 which may be unattached and reversible, as shown, or may be secured to the frame.

Directly under the seat support 19 and secured thereto are four horizontal perimeter members on the frame 10, and which are front member 25 secured on each side thereof to members 26 forming a part of the sides, and to the rear member 29 extending across the back.

As may be seen in FIGS. 3-5, only one side of the chair is shown, but the side member 26, as well as the structure extending downwardly therefrom, has its equal counterpart on the other side of the chair. Thus, secured to each member 26 is a rectangular mounting plate 30 to which the foot rest 31, its offset or remote hinge mechanism, generally designated as 32, the position locking control, generally designated as 35, and the chair base 36 are connected.

The base is generally rectangular, having a front support member 37, two side support members 38, and a rear support 41. These four members form a rigid structure supported so as to be stationary by four legs 42. Secured to each of the side support members 38 is a bracket 43 having an upwardly extending flange portion 44.

Fixedly secured to the frame plate 30, at a selected chair balancing point, is a bolt 47 extending through an opening in flange 44 so as to pivotally support the frame 10 with respect to the base 36. Thus, the chair may pivot from its upright position, shown in FIG. 4, to its reclined position, shown in FIG. 5, on the pivots 47.

The hinge mechanisms 32 are each comprised of two sets of links which extend in the space 48, as shown in FIG. 3, between the inner surface of frame plate 30 and the outer side surfaces of the base structure, including the side members 38 and the brackets 43, and laterally outwardly of the front inner frame panel member 49. The first link means is comprised of a relatively long link 50 and a relatively short link 51 which are pivotally joined adjacent one of their ends by pivot 53. The link 51 is pivotally engaged inwardly of its other end 54 on a pivot post 55, fixedly secured to plate 30, and which forms the shaft of the control 35. The outer end of link 50 is pivotally secured to a foot rest bracket 56 by means of a rivet 59. It should be noted that in FIG. 1 the bracket 56 and the pivot points thereon are hidden to provide a better appearance.

The second set of links forming the offset hinge 32 is comprised of links 61 and 62, pivotally connected by a rivet 65. The outer end of the link 61 is pivotally connected to the bracket 56 on the foot rest by means of a rivet 66. Intermediate the ends of the link 62, it is pivotally connected by rivet 67 at an intermediate point to the link 50 to connect the two sets of links. The other end 68 of link 62 is pivotally connected on a rivet 69 extending from the plate 30.

Extending from the end 68 of the link 62 is a laterally

inwardly offset, short lever arm 71, pivotally secured to an actuating or integrating link 72 by a rivet 73. The forward lower end of the link 72 is pivotally engaged by rivet 74 to the base bracket 43.

As best seen in FIG. 5, the foot rest 31, secured to the offset hinge mechanism 32 by means of bracket 56, has an inner transverse support member 77, covered by an upholstered outer portion 78 having an outer contact surface 76.

As best seen in FIGS. 3-8, the control mechanism 35 is comprised of two rollers 79 and 80 mounted adjacent the end 54 of the link 51, spaced inwardly from the former with their axes in alignment with each other and parallel to the longitudinal direction of the link 51. Extending inwardly from the rollers, with respect to the sides of the chair, is a cylindrical member 82 slidably engaged on the pivot or control shaft 55. The shaft 55 has a square portion 83 which is engaged with a square opening 84 in the cylinder 82 to prevent the latter from rotating. The central portion of the inner face of the cylinder 82, directed toward the outer portion of the chair, is countersunk at 85 so as to provide an outer annular face 88 having two pairs of generally concave pockets or recesses. Each recess of each pair is diametrically opposite of the other in the same pair. One pair of the recesses 89 is relatively shallow, having a sloped surface 90 to permit easy egress of the rollers therefrom. The other pair of recesses 91 are deeper than the former and have a sharper drop so as to make it more difficult for the rollers to move outwardly thereof.

In FIGS. 3, 4 and 7, where the chair is in the upright position and the foot rest is retracted, the rollers 79 and 80 are in the shallower recesses 89 so as to permit the relatively easy reclining of the chair and the projection of the foot rest. In FIGS. 5 and 8, in which the chair is in the reclined position, by the pivotal movement of the link 51, the rollers were rotated with respect to the cylinder 82 so as to move them into the deeper recesses 91.

The cylinder 82 is biased into contact with the rollers by means of the coil spring 94 surrounding the shaft 55. The control devices are adjusted by a wing nut 95. The adjustment relates to the weight and the strength of the user of the chair and in each case to recline the chair or to move it into its upright position, the force of the springs 94 must be overcome to move the roller out of the respective recesses.

In operation, the chair is reclined with the user in the sitting position, by exerting a force with his back against the back of the chair to tend to move it into a reclined position. As indicated, this force must overcome the force of the springs 94, and when it does, the frame 10 of the chair pivots with respect to the base 36 on the pivots 47. As this occurs, the forward part of the chair rotates upwardly so that the lever arm 71 on the link 62 exerts a pull on the actuating or integrating link 72 and since the link 72 cannot be moved upwardly very far, it acts to rotate the link 62 on its pivot 69. The rotation of the link 62 moves the links 50 and 61 upwardly and outwardly, the link 50 causing the link 51 to rotate so as to move the rollers from the recesses 89 into the recesses 91 of the control device.

As the foot rest 31 is moved upwardly and outwardly by the action of the links 50 and 61, it moves in a true arc 96 of a circle having its center on a virtual hinge line 65 which is formed in a substantially straight line at the intersection of the plane of the front surface 76 of the foot rest 31 and the plane of the top of the seat. In the embodiment shown, the center of the arc of travel of the foot rest is at the upper forward corner 97 of the seat and the surface 76 is always a part of a radius of the arc. As the leg rest moves in a true arc with the seat edge being the center, the chair may be closed and moved to its upright position with a light pressure of the legs on the foot rest and the remote or offset hinge mechanism cannot be damaged during this operation; that is, the leg rest

moves downwardly just as the legs do on their hinges in the knees which are generally located by a user adjacent to the seat edge 97.

As the center of the arc is at 97, the contact surface on the foot rest and the center 97 are always in a straight line, irrespective of the location of the foot rest so that the foot rest can be made continuous with the seat as disclosed in my co-pending application filed August 18, 1958, entitled Adjustable Chair, Serial No. 755,471, which is going to issue on November 27, 1962, as U.S. Patent 3,065,989. By having the center of the arc on a virtual hinge line at the seat edge 97, the user's legs will stay in the same place on the surface of the foot rest as he exerts pressure on it to close and as it moves downwardly to its retracted position. This, of course, makes it easier to close the chair and does not cause any drag on the legs of the user, which in the prior art chairs occurs from longitudinal movement of the foot rest with respect to the legs.

The foot rest can be moved through an arc having its center at a point removed from the seat edge, but this will cause some dragging of the foot rest on the user's legs. However, the remote hinge performs at different centers of arc with respect to the seat without being subject to damage from putting all the closing pressure on the foot rest.

In FIG. 9, a portion of the chair is shown without an actuating or integrating link 72 and, thus, with the structure shown, the chair would not recline. This is an example of a stationary chair in which the foot rest can be actuated by a lever 100 externally of the chair. The lever is fixed to rotate a shaft 101 which replaces the pivot 69, shown in FIG. 5, and which is fixedly secured to a link 62a, equivalent to the link 62 except that it does not have a lever 71 thereon. The shaft rotates in the plate 30 and when the lever 100 is rotated rearwardly, the link 62a is moved into the position of the link 62 in FIG. 5 so that the foot rest is moved to its projected position. The remainder of the link structure in FIG. 9 is the same as that shown in FIG. 5, including the control device 35.

In FIG. 10, a hydraulically operated piston 102 in a cylinder 103 having fluid connections 106 and 107 is used to incline the chair and project the foot rest. The cylinder 103 is pivotally mounted at 103 to the base and the piston rod is pivotally connected at 109 to the link 62. By applying pressure through the connection 107, the chair is caused to recline on pivot 47 and the foot rest is projected as shown in FIG. 5. The same hydraulic means could be used to operate a foot rest in a stationary chair by removing the link 72, the piston then merely actuating the re-

mote hinge structure. This, again, would provide a complete unit between two members to act in the same manner as a typical hinge, but without a hinge connection at the hinge axis.

5 The invention and its attendant advantages will be understood from the foregoing description and it will be apparent that various changes may be made in the form, construction and arrangement of the parts of the invention without departing from the spirit and scope thereof 10 or sacrificing its material advantages, the arrangement hereinbefore described being merely by way of example, and I do not wish to be restricted to the specific form shown or uses mentioned, except as defined in the accompanying claim, wherein various portions have been 15 separated for clarity of reading and not for emphasis.

I claim:

For use in an adjustable article of furniture, a position control comprising:

- (a) a shaft adapted to be fixed to a pivotal part of the article;
- (b) a link member adapted to be pivoted when said part is pivoted;
- (c) a pair of spaced rollers on said link member;
- (d) a body member axially movable on said shaft and fixed against rotation;
- (e) means biasing a face of said body member to be in contact with said rollers;
- (f) a first pair of spaced recesses in said face for respectively receiving said rollers when said part is in one position; and
- (g) a second pair of spaced recesses in said face for respectively receiving said rollers when said part is pivoted to a second position.
